UNITED STATES PATENT OFFICE.

JOSEPH B. CLAY, OF CEDAR FALLS, IOWA.

MANGER PARTITION.

1,261,214.

Specification of Letters Patent. Patented Apr. 2, 1918.

Application filed September 5, 1916. Serial No. 118,501.

To all whom it may concern:

Be it known that I, JOSEPH B. CLAY, a citizen of the United States, residing at Cedar Falls, in the county of Blackhawk 5 and State of Iowa, have invented certain new and useful Improvements in Manger Partitions, of which the following is a description.

My invention belongs to that general class 10 of devices known as mangers, and relates more especially to a manger partition, for separating a continuous manger extending before a number of stalls into a plurality of individual mangers of the desired size or 15 capacity. The same is particularly designed for and is applicable in stock barns employed for the housing of cattle, where it is customary to arrange a row of stalls with a continuous manger, of a design that may 20 be easily kept clean and flushed out as desired. The purpose of the partitions is to divide the continuous manger into an individual manger for each animal, so that each 25 one may secure only his allotted supply of rations.

The invention has among its objects the production of a manger partition of the kind described that is convenient, simple, compact, durable, efficient and satisfactory, 30 and which may be installed without danger of possible injury to the stock from its use. It also has as an object the production of a partition of the kind described that may be raised or moved out of operative position to 35 permit the easy cleaning of the manger, and which partition will remain in operative or inoperative position, as may be desired. It has as a further object the production of a device that may be slightly raised or given 40 an initial movement, upon which the partition will automatically rise to an inoperative position and stop without shock or jar, remaining in raised position without latches or similar locks. It has as a further object 45 the production of a manger partition which may be installed in connection with any of the styles of stall and manger equipment now on the market, either at the time of original installation of said equipment or at 50 any time thereafter without requiring reconstruction of said equipment or disassembling of the same in order to apply the partition. Many other objects and advantages of the construction herein shown and de-

scribed will appear to those skilled in the 55 art, particularly those having use for such equipment, from the disclosure herein given.

To this end my invention consists in the 60 novel construction, arrangement and combination of parts herein shown and described, and more particularly pointed out in the claims.

In the drawings, wherein like reference 65 characters indicate like or corresponding parts,

Figure 1 is a perspective view of a portion 70 of several stalls and manger, equipped with my device;

Fig. 2 is a view in elevation of a portion 75 of the same;

Fig. 3 is a side elevation of my partition in operative position;

Fig. 4 is a similar view of the same, raised to an inoperative position;

Fig. 5 is a sectional view taken substantially on line 5—5 of Fig. 3, and

Fig. 6 is a sectional view taken on line 6—6 of Fig. 3.

Referring to the drawings, in which the preferred embodiment of my invention is 80 shown, it may be mentioned that I have shown portions of two stall units, together with the manger and a portion of the floor. In the stall and stanchion constructions illustrated I have shown my preferred style, 85 which is the subject matter of separate applications heretofore filed, and not necessary to describe or illustrate in detail herein, this being merely to make clear the installation and operation of the partition. It 90 is particularly adapted for my equipment, although is substantially standard, and may be used upon any other construction or equipment. Referring to Fig. 1, 1 represents a portion of the floor, having a curb 95 2 and manger or trough 3. Ordinarily in barn equipment of this kind the stalls consist of suitable piping or bars, which are carried in the curb 2, the curbs and mangers in the present practice being made of concrete or other suitable material. My stall consists of head bars 4, each of which has one depending leg 5 secured to the curb, the opposite leg 6 being relatively short and secured to the adjacent leg 5 of the next stall 100 unit or leg. This is extended as at 6' with the end carried by the floor substantially at 105 the gutter end of the stall. The stanchions

7 are carried by the head bars 4, with their ends ordinarily anchored to the raised curb 2.

The manger 3 is ordinarily made for the whole length, or at least a portion thereof, of the row of stalls, so that it is possible and easy to remove the litter and dirt in the manger, and if desired, flush the same out. Without partitions, however, the stock may 10 push their food or rations toward an adjacent stall, or the stock in the adjacent stall may reach over and appropriate the rations of the stock in an adjacent stall. It is therefore desirable to have partitions which will 15 divide the manger into individual units, but which partitions may be moved out of operative positions to permit the cleaning of the manger, as mentioned. For this I provide the desired number of partitions, each 20 consisting of a plate 8 of suitable material, for example, sheet iron or steel, which may be reinforced or bound by the strips 9, if desired. It will be noted by referring to the drawings that the partition is so formed 25 as to closely fit the manger when in operative position, as shown in Figs. 1 and 3. To support and secure the partition in place, I provide an arm 10, to which the partition is secured by bolts 12, or their 30 equivalents for the purpose. I have shown slots 11 in the free ends of arm 10, so that the partition may be adjusted relative the arm in the desired manner. The arm 10 is suitably secured to a part of the stall structure, as shown to one of the legs 5 of the stall unit, as will be hereafter described. In the preferred construction I provide a yoke 13, to which the arm 10 is integrally connected, the two forming substantially a bell-crank, the free end of the yoke having an extension or offset 14. The arm 10 and yoke 13 are pivotally carried by a bracket 15, or its equivalent.

Referring to Figs. 5 and 6, the preferred 45 bracket 15 shown is provided with extending parts 16, through which is passed one or more bolts 17, and a nut provided for drawing the ends 16 together so as to securely clamp the bracket 15 to the upright 50 5. It will be noted by referring to Figs. 5 and 6 that the ends 16 may be spread slightly in placing the bracket 15 on the upright 5, after which they may be drawn together by the bolt, securely locking the 55 bracket on the leg 5. While any other suitable construction may be employed, it will be noted that my bracket 15 may be placed on the upright at any time after the upright has been installed, without requiring the 60 disassembling of the stall. This is of importance as the stall parts are usually set in concrete or other similar material, and even if detachably secured to the curb, it would be expensive and require considerable labor 65 to take down and then reinstall them, if

necessary to take down the structure. The bracket is provided with an extending arm 20, which is formed with an extension 21, (see Fig. 2). I have illustrated a simple method of pivotally securing the yoke to 70 the bracket 15. Referring to Fig. 6, bolts 22 are carried by the bracket and extend through the ends of the yoke, the parts being securely held together by the nuts 23, or equivalent means. Obviously the ends of 75 the yoke could not slip off the ends of the bolts even if the nuts were not employed, as the bolts are not removable except by taking off the brackets.

To maintain the partition in the operative or inoperative position, as well as to facilitate its raising, I provide a spring 24, the ends of which I secure to the extensions 14 and 21 (see Fig. 2), the same being maintained in place by cotter pins 25, or equivalent means for the purpose. I have also shown a spring 27, arranged on the upright 5, which may be employed, if desired, but it is not entirely necessary, as will be more 90 fully explained hereafter.

It will be noted by referring to Fig. 3, that when the partition is down or in operative position the spring 24 is on one side of the pivotal point of connection of the bell-crank on the bracket 15, so that the 95 spring tends to maintain the partition in down or operative position. It will also be noted by referring to Fig. 4, that when the partition is raised or lifted, and is in its inoperative position, that the weight of the 100 same, as well as the spring 24, which is on the other side of the pivotal connection, will tend to prevent the partition dropping to its operative position, shown in Fig. 3. If it is desired to raise the partition, assuming 105 that it is down, as shown in Fig. 3, the same may be given an initial upward movement in any desired manner, and after a certain movement, the line through the spring connecting the extensions 14 and 21 passes 110 the pivotal center of the bell-crank; consequently the spring will tend to throw the partition upward to the position shown in Fig. 4. It will be noted by referring to this figure that the spring 24 is slightly flexed 115 and under compression, so that the same, after a predetermined movement of the partition, tends to retard its movement and bring it to a stop without jar. The spring 27 also serves to cushion or stop the partition at its desired limit of travel in an upward direction, the yoke 13 engaging the same. Where spring 27 is not employed the yoke 13 may engage the support, as the 120 spring 24 ordinarily retards the final movement enough to prevent shock or jar.

It will be noted that the yoke serves as a stop, to limit the movement of the spring, but the same also affords a most satisfactory construction with the bearing at both sides 130

of the bracket 15; consequently the partition has no side play and is not wabbly or loose. While this might not be so serious at the time of installation, if the partition 5 were hinged or pivoted only by one bolt 22, continued wear and side warping from use might result in the partition becoming wabbly. With the construction shown, however, this is not the case, as the double bearing affords a most rigid and durable construction. It will be particularly noted 10 by referring to Fig. 4 that when the partition is raised, that but a very small part of the same extends over the manger, and that it is of very good height above the manger; consequently when the partitions are raised 15 the manger may be cleaned most conveniently and without danger of injury to the partitions. When the device is installed on my preferred stall support, it will be noted 20 that the same lies between the legs 5 and 6, where it is entirely out of the way, and where there is practically no chance for the same to strike the stock while being 25 raised. Ordinarily I have not found it necessary or desirable to connect the several partitions to each other, as they may be so readily snapped up individually, but they may be connected, if desired, as for example 30 by a bar C, shown in dotted lines in Fig. 1.

Having thus described my invention, it is obvious that various immaterial modifications may be made in the same without departing from the spirit of my invention; 35 hence I do not wish to be understood as limiting myself to the exact construction, arrangement and combination of parts herein shown and described, or uses mentioned.

What I claim as new and desire to secure 40 by Letters Patent is:—

1. In a stall manger of the kind described and in combination, a movable partition, means for movably carrying said partition, means for maintaining said partition in its 45 lowered position, said means operative to raise the partition after an initial upward movement thereof, and thereafter yieldingly limit the movement of the partition and maintain it in raised position.

2. In a device of the kind described and in combination, a partition, supporting means therefor comprising a bracket, a yoke pivotally secured to the bracket on opposite sides thereof, means for adjustably securing 55 said partition to said yoke, and means secured to said yoke and bracket for yieldingly maintaining said partition in an operative or inoperative position, said means operative to raise the partition after an initial upward movement thereof, and yieldingly oppose its movement after a predetermined travel thereof to its inoperative position.

3. In a manger device of the kind de- 60 scribed and in combination, a movable par-

tion, supporting means therefor comprising a bracket adjustably mounted on the stall structure, a yoke constituting one part of a bell crank lever and pivotally secured to said bracket on opposite sides thereof, 70 an arm constituting the other part of said bell crank lever and secured at its free end to said partition, and means for yieldingly maintaining said partition in an operative or inoperative position comprising a spring 75 having one end secured to said yoke at its free end and the other end secured to said bracket.

4. In a manger device of the kind described and in combination, a partition, supporting means therefor comprising a bracket provided with means for securing the same on the stall structure and having a stud projecting at one side, a yoke part constituting one part of a bell crank lever and 80 pivotally secured to said bracket, said yoke having a stud projecting near the free end at the side adjacent the stud on the said bracket, an arm constituting the other part of said bell crank lever and secured to said 85 partition, and means for yieldingly maintaining said partition in an operative or inoperative position as desired comprising a spring having one end secured to the stud 90 on said yoke, and the other end to the stud 95 on said bracket.

5. In a stall and manger device of the kind described and in combination, a movable partition and means for supporting and controlling said partition comprising a bracket 100 provided with means for securing the same to a part of the stall structure, a bell crank lever consisting of a yoke pivotally secured to said bracket on opposite sides thereof, and an arm at one side of the yoke secured 105 to said partition, a spring secured to said bracket and to said yoke adjacent the free end thereof, whereby when the partition is in operative position the spring will extend above the pivotal connection of the yoke and 110 said bracket, and when the partition is in raised position the spring will lie below the pivotal connection.

6. In a stall and manger device of the kind described and in combination, a partition, means for adjustably supporting and controlling said partition comprising a bracket provided with means for securing the same to a part of the stall frame, said bracket having a stud projecting outwardly 115 at one side, a bell crank lever consisting of a yoke having the free ends pivotally secured to said bracket on opposite sides thereof, and having a stud at the outer end on the same side as the stud on said bracket, 120 and an arm forming an extension for one side of the yoke on the opposite side of the bracket, said arm secured to the partition, a spring secured at one end to said bracket 125 stud and at the opposite end to said yoke 130

stud, said studs so arranged at points, whereby when the partition is down the spring will extend above the pivotal connection of the yoke and said bracket, and when the partition is in raised position the spring will lie below the pivotal connection.

In testimony whereof, I have hereunto

signed my name in the presence of two subscribing witnesses.

JOSEPH B. CLAY.
